TO PYRENE MANUFACTURING COMPANY, A CORPORATION OF DELAWARE.

CHEMICAL HEATER.

1,384,747.

Specification of Letters Patent. Patented July 19, 1921.

Application filed August 24, 1917. Serial No. 187,939.

To all whom it may concern:

Be it known that we, LUIS E. ECKELMANN and GEORGE E. FERGUSON, citizens of the United States, and residents of the city, county, and State of New York, have invented certain new and useful Improvements in Chemical Heaters, of which the following is a specification.

This invention relates to a chemical heater, having more particular reference to certain mechanical features of construction whereby use of the generator is facilitated.

The invention is especially adapted for application to a heater in which a liquid solution of salts containing water of crystallization is sealed up in a suitable container to prevent the inception of crystallization until desired.

The present invention has for an object to produce a container for the salt solution which carries the means for rupturing the seal and inducing crystallization, and which in addition, carries such means so disposed or arranged as to simplify to the utmost the manual operation or manipulation necessary to start crystallization.

For further comprehension of the invention and of the objects and advantages thereof, reference will be had to the following description and accompanying drawings, the various novel features of the invention being more particularly pointed out and set forth in the appended claims.

Figure 1 of the drawings is a sectional elevation of a chemical heater embodying the invention, this view being taken on the line 1—1 of Fig. 2.

Fig. 2 is a transverse sectional view taken on the line 2—2 of Fig. 1.

Fig. 3 is a horizontal section on the line 3—3 of Fig. 1.

The heater may comprise a container 1, of any suitable construction, for the heating medium, and may be used for any desired purpose.

As here shown the invention is embodied in a heater adapted for use in the place of the well known hot water bottle, the container 1 being made of metal and of flattened circular shape, with the opposite walls bowed outwardly as shown at 2 and 3 so as to stiffen the walls to prevent any buckling thereof during handling which might cause a disturbance of the salt solution and consequent

starting of crystallization. A projecting, 55 exteriorly screw-threaded, nipple 4 is formed on the container and constitutes the mouth thereof.

The solution of crystallizable salts, such as four parts of sodium acetate with three 60 molecules of water of crystallization and one part of sodium thiosulphate with five molecules of water of crystallization, is indicated at 5 and substantially fills the container. The seal is indicated at 6 above and in close 65 contact with the salt solution. This seal may be of organic material which is solid at normal temperatures and melts at a point substantially the same as the melting point of the salts, a mixture of paraffin wax and lanolin being suitable. A hermetic seal is thus formed over the salt solution when the sealing material solidifies. When a solution of crystallizable salts is sealed up in a manner 70 to prevent access of air thereto and impact 75 of the particles thereof against one another, as is accomplished by sealing as above set forth, the container may be subjected to any jolting, jarring or handling without crystallization starting as long as the seal remains intact.

Screwed upon the nipple 4 is a cap 10 which may be provided with a hinged handle 11 which permits of suspension of the heater and also facilitates screwing and unscrewing of the cap. Secured at one end to the cap and extending centrally through the latter and into the container is a rod 12 which may have a pointed end 13. This rod 12 is of sufficient length to extend through the seal 6 when the cap 10 is in place, as shown in Fig. 1.

Mounted upon this rod within the cap 10 is a plug 15 which may be made of cork and slightly tapered as shown. This plug 15 is 95 of a diameter to fit snugly in the nipple 4, the interior of which is correspondingly tapered, and thus tightly close the mouth of the container.

The plug may be secured upon the rod by 100 any desirable means, the means we have provided constituting a pair of nuts 16 and 17 threaded upon the rod 12 above and below the plug. With the plug secured on the rod in this manner it may be adjusted longitudinally to effect a proper fit in the nipple 4 when the cap 10 is screwed down on the latter.

- The heater is first prepared for use by placing the salts and sealing material there-in and heating, as by immersing in hot water, to melt the salts and sealing material, 5 with the cap 10 in place. The salts and sealing material may be placed in the container while solid, or they may be first melted separately and then poured into the container, the smaller specific gravity of the 10 sealing material causing it to rest upon the salt solution. Enough sealing material will be used to form a seal of sufficient strength to support the weight of the salt solution when the container is in inverted position.
- 15 The heater may then be suspended by the ring 11, or otherwise retained in an upright position, until the sealing material solidifies and forms a seal effectually preventing the inception of crystallization. As will be ob- 20 vious the seal solidifies with the rod 12 ex-tending therethrough and when it is desired to generate heat by crystallization of the salt solution it is only necessary to unscrew the cap 10, thus withdrawing the rod 12 from 25 the seal and leaving an opening through the latter as shown at 18 in Fig. 2, and in conse- 30 quence effecting a rupture of the seal. The resultant disturbance of the salt solution, or admission of air thereto, or both, causes crystallization to start.

The heater is again prepared for use by heating, as above set forth, with the cap 10 in place. The plug 15 acts to prevent the escape of any water vapor that may be 35 formed during heating, thus preventing any lessening of the efficiency of the heater on repeated use due to the amount of water contained therein becoming insufficient to dissolve all the salts.

40 What we claim is:

1. A chemical heater comprising a container, a crystallizable salt solution and a sealing material adapted to be melted when heated in said container, the sealing mate- 45 rial being of less specific gravity than that of the salt solution and adapted to solidify upon cooling and to form a seal preventing crystallization while said seal remains in-tact, and a device normally extending 50 through said seal and into said salt solution and adapted upon withdrawal to rupture

said seal and cause the salt solution to crys-tallize.

2. A chemical heater comprising a con-tainer, a crystallizable salt solution and a 55 sealing material adapted to be melted when heated in said container, the sealing mate- rial being of less specific gravity than that of the salt solution and adapted to solidify upon cooling and to form a seal preventing 60 crystallization while said seal remains in-tact, a cap for closing the mouth of said con-tainer, and a device carried by said cap and extending through said seal and into said salt solution when the cap is in place, said 65 device being adapted to be withdrawn from the said seal by removal of the cap, rupturing the seal and causing the salt solution to crystallize.

3. A chemical heater comprising a con-tainer, a crystallizable salt solution and a 70 sealing material adapted to be melted when heated in said container, the sealing mate- rial being of less specific gravity than that of the salt solution and adapted to solidify 75 upon cooling and to form a seal preventing crystallization while said seal remains in-tact, a cap and a plug attached thereto for closing the mouth of said container, and a device carried by said cap and extending 80 through said seal and into said salt solution when the cap is in place, said device being adapted to be withdrawn from the said seal by removal of the cap, rupturing the seal and causing the salt solution to crystallize. 85

4. A chemical heater comprising, a con-tainer adapted to hold both a heating me- 90 dium and a seal of organic material there- for, a cap covering the mouth of said con-tainer, a rod carried by said cap and pro-jecting into said container and adapted to 95 extend through the said seal when the latter is in position, a plug secured upon said rod and projecting into and tightly closing the mouth of the container, and means for ad-justing said plug longitudinally upon said rod.

Signed at city, county and State of New York, this 21 day of August, 1917.

LUIS E. ECKELMANN.
GEORGE E. FERGUSON.
